UNITED STATES PATENT OFFICE.

HERBERT HENRY BERRY, OF LONDON, ENGLAND.

IMITATION FIRE.

Application filed January 3, 1924, Serial No. 684,264, and in Great Britain January 25, 1923.

In the specification of my Letters Patent No. 186,234 I have described an imitation fire in which a dog grate or other suitable "fire place" contains imitation fuel under or 5 behind which are electric lamps or gas lights and rotary flicker-producing devices. Adjacent to the dog grate or fire place is a reflector and one or more heating elements, say for example, electric resistances, the arrangement of the reflector and the said heating agents being such that the heat from the latter is directed or thrown by the reflector across the "fire" into the apartment or place in which the imitation fire is installed.

The present invention has reference to fires of this kind and consists in modifications or improvements therein.

According to the present invention instead of employing reflectors as described in the said specification, or it may be in combination therewith, I use a reflector positioned above the fire and having its lower part more forwardly arranged than the upper or central part and preferably so constructed that the said reflector appears to be a canopy above an ordinary fire and I use the front face of this canopy-reflector to direct heat rays received by it from a heating element positioned above the fire and preferably hidden as by placing it behind the frieze or equivalent of the mantelpiece within which the fire is placed.

I may also construct the back part or the back upper part, of the fire and so position a reflector according to my cited specification, and other than the canopy reflector, and which I will refer to as the back reflector so that light from the lamps or equivalents is directed through that part on to the back reflector. This may be accomplished by simply leaving the said part open or by placing it in panels or frames adapted to colour the light or break it up.

With openings or light gaps of suitable sizes and which may be quite irregular in shape and with the oppositely rotating flicker devices I am able to obtain on the back reflector waving tapered reflections which very closely resemble flames, in addition to which part of the fuel may be reflected and thus the appearance of the fire is greatly enhanced.

I may if I so desire construct back reflectors to radiate heat below the fire as well as above it by using extended back reflectors or by employing additional back reflectors suitably positioned at the lower back part of the fire.

I will now describe my invention with reference to the accompanying drawings in which:

Fig. 1 is substantially a sectional view of a fire place containing a fire and one of my canopy reflectors above the fire as well as a back reflector substantially behind the fire.

Fig. 2 shows the same fire place and other parts in front elevation.

Figs. 3 and 4 show coloured screens.

Fig. 5 shows in outline an arrangement including the use of one of these screens and

Fig. 6 shows a modification.

In Figs. 1 and 2 the fire *a* is substantially as that described in my cited specification but the lamp *b* has two oppositely rotating fans *c* above it. Behind the fire is a reflector *d* adapted to reflect light from the fire in a forward direction. The rays of light are broken by the fans *c* and because these fans rotate in opposite directions these rays are produced in the form or appearance of substantially vertical and flickering flames as seen at *x*.

Above the fire I provide a reflector *e* which has the appearance of an ordinary smoke canopy and I position a heating element at *f* which is adapted to throw heat on to the canopy-reflector which re-directs the heat rays outwardly as seen by the arrows *z*.

For the purpose of getting a more broken effect in the light on the reflector *d* I may fit a perforated plate such as *g* Fig. 3, into the back of the fire, or instead of using a perforated plate I may use a coloured screen such as *h*, Fig. 4.

In Fig. 5 the general construction is much the same as that shown in Fig. 1 but instead of fitting a panel substantially across the back of the "fire" I may leave an opening at *i* along the upper part of the back and I may use a colouring means, say a screen, in it if desired. In these figures I have not shown a heating element for the reflector *d* but the same may be used, as in my cited specification, if desired.

Fig. 6 is a reproduction of Fig. 5 with the addition of a heating element at *h* adapted in conjunction with the reflector *l* to throw heat rays across the hearth under the fire.

I have shown a canopy-like reflector of plain design but it may be ornamental and be supported in any desired manner including by means of uprights from the frame of the fire in which case the fire and the canopy-reflector would be a unit in which case the heating element for the canopy-reflector could be carried by arms or a bracket extending therefrom. Other modi-

fications are possible within the scope of the following claim.

What I claim is:

A heat reflecting element for use with imitation fire constructions, including a reflector arranged above the imitation fire and simulating a smoke canopy for such imitation fire, the outer surface of the reflector being downwardly and outwardly curved to reflect heat rays from an independent source of heat.

In witness whereof I have hereunto set my hand.

HERBERT HENRY BERRY.
